Application December 5, 1936, Serial No. 114,488
In Germany December 19, 1935

6 Claims. (CL. 46—87)

This invention relates to an inflatable toy balloon having an outlet nozzle for the introduced air for the purpose of imparting a lift to the balloon. In this connection it is necessary that the aperture of the nozzle be made comparatively large, as otherwise the lift will be too small. A comparatively large nozzle aperture has, however, the disadvantage that the air within the balloon escapes too quickly so that the balloon again falls to the ground in a very short time.

It has been found that the lift is considerably assisted if the nozzle is made in cup-like form, i. e., is furnished with a bottom which contains the outlet aperture, and the edge of the said outlet aperture is passed inwardly upwards. If it is desired to produce a hissing or whistling noise during the time when the balloon is in the air, there is provided in spacial disposal to the first bottom a second bottom which is also furnished with an outlet aperture.

To assist the lifting effect and at the same time to cause the balloon to remain for a longer time in the air there may be provided according to the invention, in place of a simple nozzle, an injector-like compound nozzle, the outer portion of which possesses in its wall openings for sucking in air from the outside. To increase the injector effect the inner portion of the nozzle is furnished with a smaller orifice than the outer portion, and preferably the arrangement will be such that the distance between the two orifices is capable of adjustment. This adjustment may be obtained by a threaded connection between the inner and outer portions of the nozzle. This adjustment of the spacing between the two apertures may be utilized to compensate any difference in the tension of the balloon material. The air passing at a high speed through the constricted inner nozzle picks up within the outer nozzle air from the outside passing in through the openings in the outer nozzle, which outer air is expelled through the outer nozzle and assists to impart the lift.

Since the outlet aperture of the inner nozzle, owing to its constricted form, is not adapted for rapid inflation of the balloon, it is desirable to furnish the inflation tube of the balloon with a sleeve, over which the nozzle may be fitted after the inflation. The inflation tube may be closed in the known fashion by means of a resilient clip.

Various embodiments of the invention are illustrated by way of example in the accompanying drawing.

Fig. 1 is a view of a balloon showing in section a nozzle constructed in injector-like form.

Fig. 2 shows the inflation tube with the sleeve, and

Fig. 3 is an elevational view of the two-part nozzle removed from the sleeve.

Fig. 4 shows a resilient clip for closing the inflation tube of the balloon.

In the embodiment according to Figs. 1 to 3 the nozzle is constructed as a compound nozzle acting in the manner of an injector, there being fitted or screwed over the cylindrical part of the nozzle ¹⁰ c^1 a second nozzle d^1 , the orifice of which is in certain spacial disposal to the orifice c^2 of the inner nozzle c^1 and the wall of which is furnished with openings d^2 for sucking in auxiliary or secondary air. The aperture of the outer nozzle d^1 ¹⁵ is preferably larger in cross-section than the aperture c^2 , and the spacing between the two nozzles is capable of regulation, for example by the threaded connection between the cylindrical portions. The two-part nozzle is fitted by means of ²⁰ the cylindrical portion of the inner nozzle c^1 on to a sleeve b^1 , over the end beading b^2 of which there is slipped the inflation tube a^2 of the balloon a^1 . The nozzle fitting over the sleeve b^1 also protects the latter against contamination when the ²⁵ balloon after escape of the air again falls to the ground.

For the purpose of inflating the balloon a^1 the two-part nozzle c^1 , d^1 is capable of being removed from the sleeve b^1 , and the inflation is performed ³⁰ by means of the latter. When sufficient air has been introduced the inflation tube a^2 is closed by application of the resilient clip e^1 , as indicated in dash-dotted lines in Fig. 6. After the nozzle c^1 , d^1 has again been fitted on the sleeve b^1 the ³⁵ balloon is ready for use, and will commence to rise upon removal of the clip e^1 . The air passes out at high speed through the orifice c^2 , sucking up auxiliary air through the openings d^2 , and escapes together with this auxiliary air through ⁴⁰ the orifice in the outer nozzle d^1 . This latter orifice is of such size that a sufficient degree of lift is obtained, whilst the escape of the air from the balloon is determined by the narrow aperture c^2 , so that in consequence the balloon will remain ⁴⁵ in the air for a comparatively long time before its supply of air has been fully consumed.

It will be understood that no limitation is made to the specific forms of embodiment shown, and that numerous modifications are quite possible ⁵⁰ within the meaning of the above description and the annexed claims without departing from the spirit of the invention.

What I claim as new and desire to secure by Letters Patent is:—

1. An inflatable toy balloon, comprising, in combination, an outlet nozzle adapted for imparting a lift to the balloon under the pressure of the gaseous medium previously introduced, 5 said nozzle having the form of an injector and possessing lateral openings in its outer wall arranged in such relation to the inner outlet nozzle as to enable auxiliary air being sucked in and mixed with the gaseous medium ejected through 10 the inner nozzle.
2. An inflatable toy balloon according to claim 1, and characterized in that the outlet aperture in the outer nozzle portion is larger than the outlet aperture in the inner nozzle portion.
- 15 3. An inflatable toy balloon, comprising, in combination, an outlet nozzle adapted for imparting a lift to the balloon under the pressure of the gaseous medium previously introduced, said nozzle consisting of two members which are 20 adjustable relatively to each other, each member having a contracted outlet aperture, the outlet aperture of the outer member being larger than the outlet aperture of the inner member, and lateral openings in the outer member arranged 25 in such relation to the inner outlet aperture as to enable auxiliary air being sucked in and mixed with the gaseous medium ejected through the inner nozzle.
4. An inflatable toy balloon according to claim 3, in which said two members are interconnected 30 by screw-threaded engagement.
5. An inflatable toy balloon, comprising, in combination, a rigid sleeve adapted to be connected to the balloon, an outlet nozzle adapted for imparting a lift to the balloon under the pressure of the gaseous medium previously introduced, 5 said nozzle being further adapted to be detachably held on said sleeve and having the form of an injector with lateral openings in its outer wall arranged in such relation to the inner outlet nozzle proper as to enable auxiliary air 10 being sucked in and mixed with the gaseous medium ejected through the inner nozzle.
6. An inflatable toy balloon, comprising, in combination, a rigid sleeve adapted to be connected to the balloon, an outlet nozzle adapted 15 for imparting a lift to the balloon under the pressure of the gaseous medium previously introduced, said nozzle being further adapted to be detachably held on said sleeve and consisting of two members which are adjustable relatively to 20 each other, each member having a contracted outlet aperture, the outlet aperture of the outer member being larger than the outlet aperture of the inner member, and lateral openings in the outer member arranged in such relation to the 25 inner outlet aperture as to enable auxiliary air being sucked in and mixed with the gaseous medium ejected through the inner nozzle.
